ATTORNEY

UNITED STATES PATENT OFFICE

149,507

DESIGN FOR A BOTTLE OR THE LIKE

Frank McIntosh, New York, N. Y., assignor to Letheric, Incorporated, New York, N. Y., a corporation of New York

Application September 20, 1946, Serial No. 133,449

Term of patent 14 years

(Cl. D58—6)

To all whom it may concern:

Be it known that I, Frank McIntosh, a citizen of the United States, residing at New York city in the county of New York and State of New York have invented a new, original, and ornamental Design for a Bottle or the like, of which the following is a specification, reference being had to the accompanying drawing, forming part thereof.

Fig. 1 is a front elevational view of a bottle or the like, embodying my new design;

Fig. 2 is a side elevational view; and

Fig. 3 is a top plan view thereof.

I claim:

The ornamental design for a bottle or the like, substantially as shown.

FRANK McINTOSH.
